UNITED STATES PATENT OFFICE

2,438,291

ANGLE DRIVE CONSTRUCTION

Charles A. Koza, Pittsburgh, Pa.

Application April 13, 1943, Serial No. 482,874

6 Claims. (Cl. 74—423)

1

This invention relates to power drives and more particularly to drives for angle drills used in drilling holes in places that are otherwise inaccessible to a straight drill. The principal object of this invention is to provide a novel construction for the angle drive which will hold the drive and its driving gears and parts in correct alignment and adjustment.

Another object of this invention is to provide an angle drill with novel adjusting means for taking up the wear of the moving parts thereof.

Another object of this invention is to so construct the combination and the parts thereof that the parts can be easily assembled and adjusted and taken apart for the replacement of worn parts.

Another object of the invention is to make the combination so that the drill will be self lubricating.

These and other objects of the invention will be illustrated in the drawings, described in the specification and pointed out in the claims thereof.

In the drawing:

Figure 1 is the longitudinal transverse section of the drill.

Figure 2 is an enlarged sectional view of the right hand portion of Figure 1.

Figure 3 is an enlarged sectional view of a part of the drill containing a modification of or improvement on the drill shown in Figures 1 and 2, the improvement including a second elbow and parts associated therewith.

Figure 4 is a bottom plan view of the drill shown in Figure 3 on the same scale used in Figure 1 and showing the second elbow in a random position.

Figure 5 is a top plan view of the outside of the elbow of the angle drill shown in Figure 3 with the second elbow and the sleeve and associated parts thereof removed, the outside threads being covered with a collar.

In the drawings like reference numerals indicate like parts.

In the drawing reference numeral 1 indicates the elbow of the drill having the two chambers 2 and 3 therein which chambers are shown at right angles to each other although it will be understood that the chambers can be placed at an angle of 135° to each other or any other desired angle. Each of the chambers 2 and 3 has a female thread on the inside thereof. Engaged with the chamber 2 is an extension sleeve 4 which is threaded with a male thread as indicated at 5 and has an extension extending beyond the thread as indicated at 6. This sleeve is provided

2

with holes 7 spaced circumferentially thereof. This sleeve is assembled with the elbow and its chamber by screwing the parts together until the desired adjustment is secured as will hereinafter be presently explained.

Before the sleeve 4 is assembled with the chamber 2 a shaft 8 having a bevel gear 9 on the inner end thereof is inserted therein. This bevel gear is formed with a reduced end 10 and an overhanging shoulder 11 which shoulder bears on the inner end of the sleeve 4. The reduced end 10 is hollow and has a female thread therein with which a male thread 12 on the inner end of the shaft 8 makes threaded engagement by which the gear and the shaft are held together in one piece.

When the gear 9, shaft 8 and sleeve 4 are assembled, the sleeve is joined to the chamber 2 by screwing it into the chamber until its bevel gear 9 has reached the desired position. The sleeve 4 has a shoulder 13 thereon which engages with the outer end of the chamber 2 which keeps the sleeve from extending too far into the chamber. The inner end of sleeve 6 provides a bearing for the reduced end 10 of the bevel gear and the outer end of the sleeve provides a bearing for shaft 8 as indicated at 14. As shown at 15 an oil space is provided between a large part of the shaft 8 and the inside of the sleeve in which oil or grease can be held for the purpose of lubrication. The holes 7 are provided so that oil can work out between the sleeve and the housing so that the bevel gear, etc. will be amply lubricated. The extension 6 is enlarged at the inner end to make a sliding fit with the inside of the chamber and when the parts are assembled there is no lost motion. The sleeve 4 and the chamber 2 form a long handle for the tool.

In the chamber 3 a female thread 20 is provided. A short sleeve 21 is provided having a male thread on the inner end thereof, the outer end of the sleeve being formed with a shoulder or flange 22. In this sleeve is mounted to rotate a bevel gear 23 which gear has a reduced end 24 surrounded by shoulder 25 on the back of the gear. The gear 23 meshes with the gear 9 and is driven thereby. The reduced end 24 has a female thread therein and carries a drill holder 26 which has a shoulder 27 on the outer end thereof, the inner end being reduced and having a male thread thereon which engages with the female thread in the reduced end 24 of the gear. Before the sleeve 21 is inserted in the chamber 3, the bevel gear and its reduced end are placed in engagement with the sleeve 21 and the sleeve 21 is then screwed into place in the chamber 3.

The direction of the rotation of the bevel gear 23 is normally clockwise and the direction of the rotation in the gear 9 is normally counterclockwise, although it is understood that the direction of these rotations may be reversed. There will be some tendency of the sleeve 4 and extension 6 to rotate in the same direction with the gear 9 and for the sleeve 21 to rotate in the same direction to the gear 23 which would unscrew them. To offset or neutralize this tendency the threads that couple the chamber 2 and the sleeve 4 are preferably right hand threads and the threads that couple the sleeve 21 in the chamber 3 are preferably left hand threads, the tendency in each case being to rotate the sleeves inwardly toward the elbow rather than rotate them out away from the elbow.

The end of each bevel gear 9 and 23 is blunt. At the elbow of the drill is placed a ball 30 held in place by a short screw 31 such as is shown in my prior Patent #2,229,509. The ball can be inserted through the screw hole or can be inserted through either one of the chambers. This ball takes the inward thrust from the bevel gears, the outer thrust being taken by the ends of the sleeves 4 and 21.

The parts are formed preferably in the first instance so that when the shoulder 13 is screwed against the end of the sleeve 2, the gear 9 will be in its correct position. The same is also true in the forming of the sleeve 21, the distance between the inner end of the sleeve and the shoulder 22 being such that when the shoulder 22 abuts against the end of the chamber 3 the gear 23 will be in a correct position. As the ends of the sleeves wear the wear can be taken up by the insertion of a washer either on the shoulder on the bevel gear 9 and 23 or on the shoulder 13 and 22 or the shoulder 13 and 22 can be turned down to compensate for the wear and correct the adjustment.

In Figures 3 and 4 I have shown a modification of the drill shown in Figures 1 and 2 the modification consisting of the addition of another angle so as to make it into a double angle drill. In this form the short chamber 3a is threaded on the outside with a male thread as indicated at 31a as well as being threaded on the inside with a female thread. An internal sleeve 32 is provided which sleeve has a collar 33 formed integral thereon in the middle thereof. This sleeve is threaded on the outside at the inner end and is left smooth on the outside at the outer end. It is left smooth on the inside. A bevel gear 34 is mounted to turn at one end of the sleeve and a bevel gear 35 is mounted to turn at the outer end of the sleeve. These gears are coupled together in a single unit by the stud 36 which is threaded into the reduced end of each of the gears so that the two gears revolve together as a unit on the sleeve 32, the sleeve 32 forming a bearing therefor. The threaded end of the sleeve 32 is screwed into the chamber 3a until the collar thereon abuts against the end of the chamber. A coupling or external sleeve 37 is formed with a female thread therein which thread engages with the male thread on the outside of the chamber 3a. A second elbow 40 is provided having a bevel gear 41 therein with a reduced end 42 surrounded by a sleeve 43 which sleeve has a flanged end 44, the sleeve and flange being similar to the sleeve 21 and flange 22 shown in Figures 1 and 2. The elbow 40 has chambers 45 and 46. The sleeve 43 has a male thread on the outside which engages with the female thread on the inside of the chamber 45 of the elbow 40. This elbow is also pro-

vided with a ball 46 held in place by a screw 47 which ball forms a thrust bearing for the bevel gears 35 and 41.

In Figure 5 I have shown a set screw 60 adapted to engage with the screws 31 and 47 for the purpose of holding those screws in place when finally adjusted.

The chamber 48 of the elbow 40 is threaded on the outside and is smooth on the inside. On the inside the chamber 48 makes a sliding fit with the lower end of the sleeve 32. The chamber 48 is threaded on the outside with a left hand thread, the thread on the chamber 3a being a right hand thread. The coupling 37 has a female thread therein, the thread at the top being a right hand thread and the thread at the bottom being a left hand thread. By engaging the threads of the coupling 37 with the threads on the chamber 3a and the chamber 48 and turning the coupling 37 in one direction, the ends of the two chambers are brought toward each other and into abutment with collar 33 by which they are spaced apart. If this coupling is loosened the chamber 45 of the elbow 40 can be turned in any direction and can then be clamped in place by the coupling 37.

It will also be understood that there is no thread on the outside of the collar 33. With the parts so assembled a drill holder similar to 26 shown in Figure 2 is inserted in the reduced end 42 of the gear 42 and is driven by the shaft 8 through the two pairs of bevel gears.

The assembly including the gears 34 and 35 will be accurately fitted in the first place and the endwise adjustment of the assembly will be made by the adjustment of the chambers. The bevel gear 41 can be adjusted endwise by turning the sleeve 43. The bevel gear 9 is adjusted by turning the sleeve 4 and the intermediate second and third bevel gears 34 and 35 float as a unit between the gears 9 and 41.

In Figure 5 I have shown the outside of the elbow shown in Figure 3 which is identical with the elbow shown in Figure 1 except that it has a male thread on the outside of the short chamber. In Figure 5 I have shown this male thread covered or protected by a collar 51 which collar will be kept in place thereon if the attachments shown in Figure 3 are removed from the elbow that is if the double angle drill shown in Figure 3 is converted back into a single angle drill as shown in Figures 1 and 2.

It will also be understood that the angles of the elbows of the drill shown in Figure 3 can be any angle desired other than 90° and it will also be understood that with the drill assembled either as a single angle drill or a double angle drill, a drill will be inserted in the tool holder 26 and on the rotation of the shaft 8 will be turned thereby.

I claim:

1. In an angle drive the combination of a tubular housing having the form of an elbow with a chamber in each end of the elbow, a second elbow also having two chambers, an internal sleeve connecting the adjacent chambers of said elbows, a collar on said sleeve which is engaged by the adjacent ends of the chambers and by which the chambers are spaced apart, and an external sleeve making threaded engagement with the two adjacent chambers and coupling them together.

2. In an angle drive the combination of a tubular housing having the form of an elbow with a chamber in each end of the elbow, a second elbow also having two chambers, an internal sleeve connecting the adjacent chambers of said elbows, a collar on said sleeve, which is engaged by the

adjacent ends of the chambers and by which the chambers are spaced apart, an external sleeve making threaded engagement with the two adjacent chambers and coupling them together, a first and second bevel gear mounted to rotate in the first elbow, a third and fourth bevel gear mounted to rotate in the second elbow, and means for connecting the second and third bevel gears together so that the first bevel gear drives the second, third and fourth bevel gears.

3. In an angle drive the combination of a tubular housing having the form of an elbow with a chamber in each end of the elbow, a second elbow also having two chambers, an internal sleeve connecting the adjacent chambers of said elbows, a collar on said sleeve, which is engaged by the adjacent ends of the chambers and by which the chambers are spaced apart, an external sleeve making threaded engagement with the two adjacent chambers and coupling them together, a first and second bevel gear mounted to rotate in the first elbow, a third and fourth bevel gear mounted to rotate in the second elbow, means for connecting the second and third bevel gears together so that the first bevel gear drives the second, third and fourth bevel gears, a shaft for driving the first bevel gear, and a threaded means for adjusting said shaft and its bevel gear forward or back in its chamber.

4. In an angle drive the combination of a tubular housing having the form of an elbow with a chamber in each end of the elbow, a second elbow also having two chambers, an internal sleeve connecting the adjacent chambers of said elbows, a collar on said sleeve which is engaged by the adjacent ends of the chambers and by which the chambers are spaced apart, an external sleeve making threaded engagement with the two adjacent chambers and coupling them together, a first and second bevel gear mounted to rotate in the first elbow, a third and fourth bevel gear mounted to rotate in the second elbow, means for connecting the second and third bevel gears together so that the first bevel gear drives the second, third and fourth bevel gears, a shaft for driving the first bevel gear, a threaded means for adjusting said shaft and its bevel gear forward or back in its chamber, a shaft driven by the fourth bevel gear and a threaded means for ad-

justing the fourth bevel gear and its shaft forward and back in its chamber.

5. In an angle drive the combination of a tubular housing having the form of an elbow with a chamber in each end of the elbow extending outwardly therefrom, said housing having a female thread at the outer end of one chamber, a long sleeve having a reduced end, said sleeve having a threaded portion on the reduced end about midway between the ends of the sleeve with the shoulder adjacent said threaded portion, the reduced end of the sleeve engaging in the chamber and having its threaded portion engaged with the female thread of the chamber with which it engages, a bearing inside of the sleeve at the outer end thereof and a bearing at the inner end of the sleeve, said sleeve forming an extension to the chamber to which it is attached and with the chamber forming a handle for the housing.

10 6. In an angle drive or the like, an elbow, a second elbow having one end articulated with but removable from the first mentioned elbow, meshing bevel gears journaled in each elbow, means connecting the adjacent gears of the two elbows, and means removably securing the articulated elbow to the first mentioned elbow whereby one of said elbows may be used independently of the other, said last-mentioned means being a coupling sleeve having threaded engagement with

15 20 25 30 both said elbows.
